ATTORNEY.

UNITED STATES PATENT OFFICE.

DELAWARE J. HOOD, OF PHILADELPHIA, PENNSYLVANIA.

TALKING MACHINE.

1,422,712.

Specification of Letters Patent. Patented July 11, 1922.

Application filed April 24, 1919. Serial No. 292,430.

To all whom it may concern:

Be it known that I, DELAWARE J. HOOD, a citizen of the United States, residing at Philadelphia, county of Philadelphia, and State of Pennsylvania, have invented a new and useful Improvement in Talking Machines, of which the following is a full, clear, and exact description, reference being had to the accompanying drawings, which form a part of this specification.

The object of my invention is to provide a talking machine and a support and enclosure therefor, so adapted one to the other as to enhance the beauty of the whole, reduce the required floor space, and at the same time provide an amplifier of relatively large area.

My invention comprises a talking machine all the parts of which, including the motor, sound record table, sound arm and amplifier, are mounted on the rear of a door which may constitute the front of an enclosure. The enclosure may be portable, but I prefer to build it permanently into a room, the amplifier being arranged vertically above the record table and opening through the upper part of the door itself, thereby directing the sound into the upper portion of the room.

A preferred embodiment of my invention is shown in the accompanying drawings, wherein—

Fig. 1 is a front view of my invention; Fig. 2 is a sectional view; Fig. 3 is a detached front view of the sound amplifier; Fig. 4 is a detail sectional view through a portion of the door and the portion of the amplifier adjacent thereto; and Fig. 5 is a detail view of the adjustable sound box.

The door *a* designates a vertically disposed support which may be in the form of a door and arranged to swing on hinges. It may be utilized as the front of any enclosure, such as a tall, shallow closet built into or against the wall of a room. Mounted on a bracket *b*, secured to the inside of the door, is a casing *c* containing the motor, which drives a rotary table *d*, on which a sound record disc is adapted to be placed in the usual manner.

Secured to the inside of the upper portion of the door is a sound amplifier. The amplifier preferably consists of a shell *e* of wood provided with two passages *f*, *f*, formed in opposite halves of the shell, each passage gradually increasing in width and depth from its lower to its upper end. The

wide outlet mouths of the two passages are separated by a thin partition *g*, the sound waves being diverted outwardly through any suitable opening in the door, as through an ornamental grill *h*.

Projecting rearward from the lower end of the amplifier is a sound tube *i* which communicates with the lower end of the amplifier. Slidable telescopically on the sound tube *i* is the upper inturned end of a sound arm *k*, which is thence curved successively inward and downward, projecting toward the sound record table in an inclined direction. A sound box *m* is sleeved on the sound arm.

The door is provided with an opening *n*, whose lower edge is about on a level with the sound record table. This opening may be closed, if desired, by a swinging door *o*. Through this opening access may be had to the machine for the purpose of depositing records on, and removing them from, the table and for lifting and replacing the sound arm. A small orifice *p* may be provided for the reception of a key for winding the motor.

Normally the door will be closed, and indeed, if desired, the door may be fixed in closed position, access being had to the machine through the opening *n*. I prefer, however, that the door shall be capable of opening like any other door, the entire mechanism of the talking machine being, however, in any event, supported on the door instead of by a cabinet independently of the door.

In operation, the sound will be transmitted through the sound box *m*, the sound arm *k*, the sound tube *i* and the amplifier *e*, the general direction of the sound being upward and thence outward through the upper part of the door and into the upper part of the room, whence it is reflected downward and properly distributed.

The motion of the sound arm and sound box across the record is in a straight line instead of in the arc of a circle, thereby enabling the stylus, as it follows the spiral of the groove, to move in the same path which the engraving stylus follows in the production of the original record. This insures a cleaner and more accurate reproduction. By this movement, also, I am enabled, by positioning the sound box so that the stylus is in line with the part of the sound arm adjacent thereto, to merely turn the sound box through an arc of 90 degrees and

thereby, without any other adjustment, position the sound box to properly cooperate either with a record groove having undulations in its base or with a record groove having undulations in its side walls.

Having now fully described my invention, what I claim and desire to protect by Letters Patent is:

A talking machine comprising a vertically disposed hinged support adapted to form a closure for a chamber, a motor casing supported on the rear side of the support, a rotary record table above the casing adapted to rotate about a vertical axis, an amplifier mounted on the rear side of the support

above the table, a sound arm connected to the lower portion of the amplifier and extending downwardly toward the table, a sound box on the lower end of the sound arm, there being an opening through the upper portion of the support communicating with the amplifier, there also being an opening through the support in the plane of the rotary table, the arrangement being such that the support can be swung on its hinges to move all of the parts out of the chamber.

In testimony of which invention, I have hereunto set my hand, at Philadelphia, Pa., on this 29th day of March, 1919.

DELAWARE J. HOOD.
